COMBINED GOLF BALL PUTTER AND RETRIEVER

Charles Reed, 820 Verde Vista, Visalia, Calif.

Filed Aug. 27, 1965, Ser. No. 86,737

Term of patent 3½ years

(Cl. D34—5)

FIG. 1 is a side elevation of a combined golf ball putter and retriever, showing my new design, the opposite side of the putter being identical to the side shown.

FIG. 2 is a somewhat enlarged top plan view thereof with the handle portion broken away for illustrative convenience.

FIG. 3 is a side elevation thereof.

FIG. 4 is a bottom plan view thereof.

FIG. 5 is a front elevation thereof.

FIG. 6 is a rear elevation thereof.

I claim:

The ornamental design for a combined golf ball putter and retriever, as shown and described.
